CHAIR

Gordon L. Duern, 100 Queen St. N., Apt. 605, and
Donald S. Griffin, 191 Filsinger Road, both of Kitch-
ener, Ontario, Canada

Filed Apr. 23, 1971, Ser. No. 137,105

Term of patent 14 years

Int. Cl. D6—02

U.S. Cl. D6—69

FIG. 1

FIG. 2

FIG. 1 is a perspective view of a chair showing our design, taken from the front and to one side, looking down obliquely; and

FIG. 2 is a perspective view of the chair of FIG. 1, taken from the opposite point in space, looking up obliquely.

We claim:

The ornamental design for a chair, as shown.
